UNITED STATES PATENT OFFICE

JOSEPH M. BARRETT, OF FOSTORIA, OHIO, ASSIGNOR TO THE SWARTWOUT COMPANY, OF CLEVELAND, OHIO, A CORPORATION OF OHIO

DRAINAGE-CONTROL SYSTEM

Application filed October 28, 1926. Serial No. 144,815.

This invention relates to the controlling of drainage from a container or condensation trap and has for its principal object the improvement of control over the devices now 5 in use.

A drainage control system according to my invention has among its principal objects the control of the water level in a container or trap so that a certain quantity of water is 10 always maintained in the container and the outlet to the container is sealed by the water therein. Such containers are generally used in connection with a steam system wherein it is desired to collect condensate at a given 15 point, but to do so without the loss of steam at that point. In the embodiment of my invention shown in the drawings, I show my control system with a container which is adapted to contain both water and steam 20 which may come from any given source. The control apparatus functions to maintain the water in the container at a level sufficient to seal the outlet of the container against the outflow of steam.

25 In my copending application, Serial 519,171 filed December 1st, 1921, since issued as Patent No. 1,609,278 as of December 7th, 1926, I have shown an apparatus with similar general objects. My present invention constitutes in a measure an improvement over my former application. It has been my experience that the container which is to be drained and in which the water level is to be 30 maintained at a certain height, accumulates not only water and steam, but also in the course of operation a certain amount of air in the steam space. The air may have substantially the same temperature as steam, but the specific heat of the air is less than the specific heat of the steam so that if a certain quantity of air accumulates in the container, it is apt to interfere with the control apparatus and render the device inoperative to 35 the extent that the outlet is unsealed and the steam is allowed to "blow through" with a resulting loss of steam and upset of the heat balance of the system. It has therefore been among the principal objects of my invention to construct a device which will not become 40 air bound and in which the effect of the pres-

ence of air in the container, will not hinder the operation of the device.

It is among the objects of my invention to effect a more sensitive operation of the water valve actuating mechanism constituting the thermo-responsive device, i. e. the pressure generator mounted at the water level of the container by means which increase the temperature differential between the liquid and gaseous fluid in contact therewith.

In carrying out the objects of my invention I have made certain other improvements, the object of which will appear from the following more detailed description. The essential characteristics will be summarized in the claims.

In the drawings, Fig. 1 is a side elevation including the apparatus comprising my control system, the discharge valve and the container; Fig. 2 is a view taken along the lines 2—2 of Fig. 1; Fig. 3 is a section taken along the line 3—3 of Fig. 2.

In Fig. 1, I show the container C having an intake 1, an outlet 2, a discharge valve 3 in the discharge pipe 4. The normal desirable water level in the container is indicated in broken lines at L. Connected to the container at the point 10 I show the conduit 15 leading through the valve 11 and connected at the point 12 to the discharge pipe 4 through the valve 13. Although not shown in the drawings, the portion of the discharge pipe 4 adjacent the point 12, may advantageously be of greater cross section than the rest of the pipe so that the fluid velocity at that point will be lower and the pressure at this point in the pipe will be subject to less variation so that the water level in the conduit 15 will not be subjected to variations by reason of the discharge of fluid through the pipe 4. The conduit 15 is shown as taking a devious path from the point 10 to the point 12, but I am particularly concerned that whatever the path of the conduit, it be so positioned to drain naturally from the point 10 to the point 12. I have shown a conduit leading from the upper or steam portion of the container to the discharge pipe, but I do not care to be specifically limited to this construction for my device will operate according to the principles 100

of my invention, if the lower end of the conduit is so connected that the conduit will naturally drain itself. Mounted on the conduit 15 and in the plane of the water lever L, I 5 show the pressure generator 20. The pressure generator 20 is shown connected to the valve 3 by means of a conduit 21 leading to a diaphragm chamber 22 wherein is disposed a diaphragm which is associated with the 10 valve 3 and is adapted to actuate it. The relationship and the cooperation between the pressure generator 20 and the valve 3 is shown in the patent to Copley No. 1,193,125 issued August 1st, 1916. As shown in the patent to 15 Copley, the pressure generator consists of a chamber lying concentric but exterior of the conduit 15 in which is enclosed an expandible fluid which is actuated in response to the relatively high temperature of steam in the 20 conduit 15, but does not respond to the temperature of the water contained in the conduit 15. The exterior of the casing comprises the pressure generator is fitted with suitable heat radiating fins, so that the fluid 25 therein may be cooled to cause a negative movement of the pressure actuatable means as the water level in the container rises.

The valve 3 is of a diaphragm actuated type wherein the valve is moved in response 30 to pressure exerted on the diaphragm, which pressure is generated in the said pressure generator 20. In my present invention and in a manner similar to that disclosed in my pending application mentioned above, the 35 valve is normally held open by the spring 5 and is forced to closed position by pressure exerted on the diaphragm. It will be seen therefore, that when the water level in the container is high that the conduit 15 which is 40 enclosed by the generator 20 will contain water which is of such temperature that the working fluid in the generator 20 will not be expanded and the valve 3 will be opened by the spring 5.

45 To insure the coolness of the water in the lower portion of the conduit 15, I provide the cooler or radiator 30 better shown in Fig. 3. The cooler 30 may be of any suitable construction but for example I show 50 one constructed of substantially the same elements as the pressure generator 20 so that a chamber 31 is formed concentrically and exteriorly of the conduit 15. The chamber 31 is enclosed by the cylindrical portions 32 along with the expansion heads 33. The 55 heads may be joined to the conduit 15 at the points 35 and 36 in a suitable manner such as brazing. The exterior of the cylindrical portions 32 may be covered with suitable 60 radiating fins 37 as shown. In the portion of the conduit 15 at a point 40, which may be about the mid-portion of the radiator, I provide a suitable obstruction to prevent the direct flow of water therethrough. By means 65 of the openings 41, I provide communication

from the conduit 15 to the chamber 31 so that the fluid passing along the conduit 15 passes through the openings 41 into and out of the chamber 31 in passage. In this manner all of the fluid is brought to contact with the cylindrical portion 32 and is cooled by contact with this portion by reason of the proximity of the radiating fins 37. The radiator 30 serves the dual purpose of cooling the water and of affording a surge chamber or reservoir for cold water.

70 In the usual operation of my device with the water level in the container C along the line L, the input into the container substantially the same as the output therefrom the plane of the water level will intersect the generator 20 so that a pressure, which may we term a "normal pressure", is exerted in the chamber 22 and on the diaphragm of the valve 3, so that the valve 3 is held open just enough to maintain a uniform discharge from the container. As the water level rises in case of an increased input into the container, the generator 20 is chilled by reason of the increase and up-flow of cold water in the conduit 15. The pressure on the diaphragm of the valve 3 is reduced so that the valve opens wider to facilitate a greater discharge. In the event of the water level in the container falling, the water level in the conduit 15 falls, 80 which permits a greater amount of steam to come in contact with the generating fluid in the generator so that greater pressure is exerted on the diaphragm of the valve 3. The valve is forced nearer the closed position and the rate of discharge is cut down so that the water seal is maintained. It will be seen that in normal operation, that the water level is maintained within certain restricted limits and the outlet of the container 90 is completely sealed.

95 There are, however, certain abnormal conditions with which it is one of the objects of my present invention to cope. As mentioned above, I have found that in the operation and use of a condensation trap that a certain amount of air accumulates within the trap. After air has accumulated down to the point 10, it will be seen that the upper part of the conduit 15 will be filled with more of less dry air. When the upper portion of the conduit 15 is filled with air and as the usual and normal condensation of steam in the conduit 15 takes place, it happens that the whole of the conduit 15 is filled with air 100 except that portion which is filled with water. In such an event, since the air has a much lower specific heat than steam or at least has a lesser conductivity, the generator 20 is chilled to such an extent that the valve 3 is allowed to become wide open. With the valve 105 3 wide open, the water rushes from the container, the seal is broken and the steam is allowed to pass freely from the intake 1 out to the outlet 2. A device according to my 110

copending application and in all prior devices, this condition would continue until by manual adjustment the air were removed from the conduit 15 and a new supply of condensate accumulated before the device would again be operative. It will also be seen that in starting to use an empty condensation trap, a similar problem presents itself.

According to my invention however, and by disposition of the generator and the conduit 15, I am assured that in starting to use the trap or in the event of an accumulation of air as described above, that as soon as the water is blown out of the trap, a free communication will be afforded between the points 10 and 12 so that air in the conduit 15 will also be blown out through the discharge pipe and the valve 3 by steam entering at the point 10. The hot steam flowing through the conduit 15 will heat the generator 20 and cause the working fluid to exert a pressure on the diaphragm of the valve 3 so that the valve will be forced to a closed position and will remain closed until the water level in the container and in the conduit 15 rises to a point where the valve may be normally operated as described above. The water will be the water of condensation formed within or entering the trap and may be of a rather high temperature.

In fact the temperature of the newly formed condensate may be such that the generator is not properly chilled. Thus I provide the radiator 30 associated with the conduit 15 as shown. By reason of the radiator 30 the water forming in the conduit 15 will first accumulate below the radiator and then will be forced upwardly through the radiator and cooled in its passage, so that the water rising in the conduit 15 from the radiator to the generator 20 will be of a low temperature even if the condensate forming in the system is quite hot. It is by this temperature differential that I am able to chill the working fluid in the generator 20, so that the valve 3 may be opened when the water level rises above the normal.

It will be seen from the foregoing that I have provided a simple and rugged control system for a condensation trap which is entirely self-operative and even self-starting. A device constructed according to my invention will automatically free itself of air binding, and will further bring itself into operation either from a cold starting or from any condition where the water seal has been broken.

I claim:

1. A drainage control system adapted to maintain a water seal over the outlet of a container to be drained, comprising in combination a container, a discharge pipe for said container, a valve in said pipe, a conduit leading from the upper portion of said container to said discharge pipe at a point be-

tween the outlet of the container and said valve, and thermo-responsive means associated with said conduit for closing said valve when the outlet of the container is unsealed and steam is present in the container.

2. A drainage control system adapted to maintain a water seal over the outlet of a container to be drained, comprising in combination a container, a discharge pipe for said container, a valve in said pipe, a conduit positioned to drain from the upper portion of said container to said discharge pipe at a point between the outlet of the container and said valve, and thermo-responsive means associated with said conduit for actuating said valve and being responsive to change in water level in said container and also actuated to close said valve when the outlet of the container is unsealed and steam is present in the container.

3. A condensation trap having an outlet wherein is maintained a water seal over said outlet, a discharge pipe, a valve in said pipe, thermo-responsive means for closing said valve and being active in response to the temperature or heat content of fluid in contact therewith, means for conducting to said thermo-responsive means fluid having a high temperature when the outlet of the container is unsealed and means associated with said last named means for cooling the fluid which is about to be raised into contact with said thermo-responsive means as the water in the container rises.

4. In a condensation trap the combination of a container having an outlet and normally having a water seal over said outlet, a discharge pipe, a valve in said pipe, pressure generator means for actuating said valve and being actuated according to the temperature of fluid in contact therewith, means for conducting to said pressure generator means, fluid having a high temperature when the outlet of the container is unsealed and means associated with said last named means for cooling the fluid which is about to be brought into contact with said pressure generator means as the water in the container rises.

5. A steam condensation trap comprising in combination, a container, a discharge pipe therefor, a branch pipe leading from the discharge pipe to the container, means for controlling the fluid outflow from the container and means associated with said branch pipe responsive to the outflow of steam from the trap for actuating said first named means.

6. In combination a container for water and steam, means for maintaining a water seal over the outlet of the container, said means including a valve for controlling the outflow from the container, a conduit leading from the steam space of the container to the discharge pipe between said valve and the outlet, pressure generator means associated with the conduit at the point of normal water

level therein and adapted to close said valve upon contact with steam in the conduit, said conduit being positioned to drain into the discharge pipe so that when the water seal is broken, steam flows from the container to the discharge pipe through the conduit and heats the pressure generator to close the valve.

7. In a steam trap, the combination of a container having an outlet, a discharge pipe leading therefrom, a valve in said pipe, a conduit directly communicating from the upper portion of the container to the discharge pipe, pressure generator means associated with the conduit at the normal water level, radiating and storage means associated with the conduit between the said pressure generator means and the discharge pipe, means connecting said pressure generator means to said valve for closing said valve when the heat content of the fluid in the conduit is raised in response to a low water level and means including said radiating and storage means for chilling the fluid which rises in the conduit when the water level rises.

8. A container for water and steam, a pipe for conducting fluid therefrom, a valve in said pipe, a cooling and storage chamber incorporated in said pipe and thermo-responsive means associated with said pipe for actuating said valve.

9. A steam trap having two outlets, one outlet positioned near the top of the trap, the other outlet at the bottom of the trap, a common discharge pipe, a conduit leading from the upper outlet and draining into the discharge pipe, a valve for controlling the flow through the discharge pipe, thermal means associated with the conduit for actuating said valve and adapted to close the valve when heated by contact with steam, whereby steam flows from the trap through said conduit and heats the thermal means to stop the outflow.

10. The combination of a container for water and steam, a discharge pipe therefor, a valve in said pipe, a conduit leading from the steam space of the container to the discharge pipe at a point between the container and the valve, and means associated with the said conduit for actuating said valve.

11. In combination, a container for water and steam, a pressure actuatable water valve for said container, fluid conducting means spanning the water level of the container and inclined to the plane thereof and communicating with the steam and water spaces of the container, a pressure generator connected to said valve comprising a closed chamber containing an expansible fluid and mounted on said means at the water level and inclined to intersect the plane of normal water level, heat dissipating means comprising parts separate from and associated with said fluid conducting means below and adjacent said generator for reducing the temperature of

fluid in said conducting means to the lowest degree at a point below and as near as possible the generator, and heat dissipating means associated with said generator whereby the heat of water in said conducting means at and immediately below the generator is 70 dissipated through said heat dissipating means.

12. In combination, a container for water and steam, a pressure actuatable water valve 75 therefor, fluid conducting means spanning the water level of the container and connected to the steam and water spaces thereof and being inclined to the plane of the water level at least near the water level, a 80 fluid pressure generator for actuating said valve and having a fluid connection therewith and comprising a closed vessel surrounding said conducting means at the water level and containing an expansible fluid 85 adapted to be put under pressure when heated by steam in said fluid conducting means, heat dissipating means for said vessel comprising radiating fins mounted on the exterior thereof, and heat dissipating means for 90 the said fluid conducting means provided to chill the water therein below the generator comprising radiating fins arranged exteriorly of said fluid conducting means below the water level and adjacent the generator. 95

13. In combination, a container for water and steam, a pressure actuatable water valve therefor, fluid conducting means spanning the water level of the container and connected to the steam and water spaces thereof, a 100 fluid pressure generator for actuating said valve and having a fluid connection therewith and comprising a closed vessel intersecting the plane of the water level and being inclined thereto and surrounding said fluid 105 conducting means and containing an expansible fluid adapted to be put under pressure when heated by steam in said fluid conducting means, heat dissipating means for said vessel comprising radiating fins mounted on the exterior thereof, and heat dissipating and water storage means in the said fluid conducting means provided to chill and store the water therein below the generator comprising a chamber having radiating fins arranged exteriorly thereof below the water level and 110 adjacent the generator. 115

14. In combination, a container for water and steam, a water valve therefor, fluid conducting means spanning the water level of the container and connected to the steam and water spaces thereof and being inclined to the plane of the water level at the water level, a thermo-responsive device for actuating said valve associated with said means at 120 the water level and inclined to the plane thereof, heat dissipating means for said device, and heat dissipating means for the said fluid conducting means comprising parts 125 separate from and associated therewith as 130

near as possible to said device and provided to chill the water therein below said device, whereby a maximum temperature difference is maintained between the steam and water in contact with said device.

15. The combination of a container for water and steam, fluid conducting means for leading fluid therefrom and through all of which means steam flows directly out of
10 said container at least during part of the initial period of operation before water is collected therein, a valve in said means for controlling the outflow of fluid from said container, thermo-responsive means associated with said fluid conducting means and positioned adjacent the path of at least part of the initial outflow of steam from the container, and means connecting said thermo-responsive means with said valve for actuating said valve, said thermo-responsive means being actuated by the heat of steam adjacent thereto and in turn acting upon said valve to close it at least when steam flows from said container through said fluid conducting means.

In testimony whereof, I hereunto affix my signature.

JOSEPH M. BARRETT.
